UNITED STATES PATENT OFFICE.

ELOF ANDERSON, OF LOS ANGELES, CALIFORNIA, ASSIGNOR TO CARL HUGO ANDERSON,
OF LOS ANGELES, CALIFORNIA.

FLEXIBLE ARCH-SUPPORT.

1,133,781.

Specification of Letters Patent. Patented Mar. 30, 1915.

Application filed March 18, 1914. Serial No. 825,674.

To all whom it may concern:

Be it known that I, ELOF ANDERSON, a citizen of the United States, residing at Los Angeles, in the county of Los Angeles and 5 State of California, have invented a new and useful Flexible Arch-Support, of which the following is a specification.

This invention relates to an arch support adapted to rest on that portion of the in- 10 sole of a shoe on which the heel and instep of the wearer is superposed and constitutes means for supporting certain bones, muscles and ligaments of the foot which are liable to become misplaced from ill-fitting shoes 15 and from hard usage and from walking on hard pavements and floors, and to prevent the falling of the arch.

An object of the invention is to provide an arch support that will automatically adjust 20 itself to the right position required to properly support the arch.

Another object is to provide a flexible construction of arch support that will not be stubborn so as to distress the foot but 25 will yield a gentle but sufficient support for the arch and will not interfere with those parts of the foot which might be distressed thereby.

Another object is to provide for an arch 30 support, a construction of the character above suggested, which will have great lasting qualities and will not be liable to squeak, and in this connection the materials of which certain parts of the arch support are constructed are important.

Other objects and advantages may appear 35 from the subjoined detailed description.

The invention may be carried out in different ways and is embodied in complementary pairs of required sizes.

The invention involves the use of certain specific materials particularly arranged with relation to each other to secure the desired results; but I do not limit the invention to 45 the exact materials specified as desirable results may be obtained even though materials are used that are only measurable equivalents of the materials herein specified.

The accompanying drawings illustrate the 50 invention in a preferred form.

Figure 1 is a perspective of a left arch support constructed in accordance with this invention. Fig. 2 is a top plan view of the arch support shown in Fig. 1 omitting the 55 major portion of the prime sole leather top,

and showing intact the horsehide glove leather bottom, the nested spring leaves and leather spring supports on said bottom and the canvas spring retainer partly ripped and turned back from over the spring leaves. 60 Fig. 3 is a longitudinal section of an arch support along a line indicated by x^3 , Fig. 2, showing a spring having three leaves instead of only two as shown in Fig. 2. Fig. 4 is a sectional elevation from line x^4 , indicated in Figs. 2 and 3, looking toward the heel. Fig. 5 is a cross-section of the arch support on line indicated by x^5 , Figs. 2 and 3, looking forward and showing a spring of three leaves. Fig. 6 is a cross section on 70 line x^6 , Figs. 2 and 3. Fig. 7 is a reduced plan of the arch support in a shoe the upper of which is cut away to expose the insole. Fig. 8 is an end elevation of the spring showing a position said spring may take 75 when the pressure of the foot depresses the arch, and also representing the position the spring will assume under the force of gravity when the spring is detached and simply laid upon the level surface of a table. 80

Arrows on the section lines indicate the direction of sight at the various sections.

The bottom 1 is made of horsehide glove leather for the reason that it is durable, 85 flexible and soft, is not liable to squeak under friction, or to stretch, is more impervious than other leathers to moisture, and will retain its softness under repeated wettings and dryings. The top 2 is made of prime oak tanned sole leather for the reason that 90 the same is a superior material for retaining its shape and its qualities of smoothness and firmness under the heat of the foot. These two members are constructed to conform to the contour of that part of the in- 95 sole under the heel and instep of the wearer; and, in the completed arch support are firmly secured together at their margins and around a central cavity 3 by means of cement 4 and stitches 5. The heel rest 6 at 100 the rear is rounded to conform to the space inside the shoe that accommodates the heel of the wearer, and in practice the heel of the wearer rests upon said heel rest. The top 2 is measurably pliable and the heel 105 rest affords a firm cushion having a close-grained smooth top surface to support the heel of the wearer.

Leather spring-supports or lifts 7, 7' are spaced apart positioned on and fixed to the 110

bottom 1 forwardly of the heel rest portion 6, and rearwardly of the front portion 8 of said bottom. Said lifts are spaced apart to form an open space α between them at the 5 front and rear of the instep portion 9 of said bottom, and said lifts support the ends of an arched spring which is made up of a plurality of leaf-springs which are of successively shorter length from bottom to 10 top. Any suitable number of said springs may be applied and in the drawing only two are shown in Figs. 2 and 4, the same being numbered respectively 10 and 11. The lower spring member 10 is provided 15 with a point 12 at the front of the mid-width of the front end of said spring and the rear end 13 of said spring extends obliquely across the axis of said bottom and of the spring. 20 The arched spring leaf 11 on top of and nested with the base spring leaf 10 is arched to conform to the middle of said base spring leaf 10 and is nested therewith to remain relatively stationary thereon, but sufficiently 25 movable thereon to accommodate the movement due to the flexure of the spring leaves. Said superposed spring leaf 11 provided with the front middle point 14 and rear oblique terminal 15, and both spring leaves 30 and the leather supports or lifts for the ends thereof are covered by a flexible retainer 16 made of canvas or other suitable material laid upon the arched springs and the leather end supports for said spring, and is secured 35 to the bottom by suitable means as cement 17 and stitches 18. The spring leaves are preferably thin plates of clock spring steel the transverse sections of said leaves being slightly crowned at the middle of the spring 40 and practically straight at the rear end of the leaf at which end the terminal is diagonal or oblique to said transverse traces and to the axis of the spring so that the outer edge 19 of the leaf and of the 45 spring is shorter than the inner edge 20 thereby to cause the spring to adjust itself aslant downward toward such outer edge. This tendency to slant is indicated most 50 clearly in Fig. 8, and is more or less effective as the pressure on the foot on the arch is greater or less. The spring leaves are separated by a rust-preventing lubricating coating 21 which is durable and lasting, being 55 made of pine tar wax or pitch, beeswax and tallow incorporated with each other while hot, the same being non-evaporable and not liable to flow out from between the leaves. Over the parts hereinbefore enumerated is 60 then applied the top 2 of prime sole leather secured by the stitches and cement, the stitches extending all around at the edges of top and bottom to hold said edges firmly together, and the cement extending all over the inner face of the top 2. 65 The hard smooth prime sole leather is suf-

ficiently flexible at the heel portion to support the heel with great comfort, and the instep portion 22 of said top will sufficiently receive the pressure from the inside of the foot to automatically adjust the arched support to the proper position beneath the foot, the leaf springs giving appropriate form to said top 2 and also to the bottom 1. 70

The spring supports or lifts 7, 7' are preferably pads of the same kind of material as 75 the bottom 1, but may be made of cow-hide glove-leather, pig skin, calf skin, or even of felt or sole leather.

The forward spring support 7 is arranged to come to a point below the hollow which 80 occurs in a normal foot at the center of the ball of the foot, and just in front of the arch. The points 12 and 14 of the spring leaves are superposed above such front spring support lift or pad 7, and in practical 85 use the spring leaves rock in a measure upon the front points while the rear digonal terminals 13 and 15 of the springs tend to favor tilting of the spring toward the flat edge of the foot and away from the inside 90 arch of the foot. This enables the arch to conform itself to a comfortable position relative to the arch of the foot whenever pressure from the foot is applied thereon. 95

I claim:—

1. An arch support comprising a bottom of durable soft flexible material, durable soft flexible spring supports spaced apart on and fixed to said bottom; an arched spring the ends of which rest on said spring supports; a retainer of soft flexible material over the spring and fixed to the soft flexible durable bottom around the edges of the spring; and a firm solid pliable top fastened at its edges to the edges of said bottom; the top and bottom inclosing the spring, the spring supports and the retainer between them and being conformed to the shape of that portion of the insole of a shoe which is under the heel and instep of the wearer. 110

2. An arch support comprising a bottom of durable soft flexible material, durable soft flexible spring supports spaced apart on and fixed to said bottom; an arched spring formed of superposed crowned leaves, the ends of one of which rest on said spring supports; a retainer of soft flexible material over the spring and fixed to the soft flexible durable bottom around the edges of the spring; and a firm solid pliable top fastened at its edges to the edges of said bottom; the top and bottom inclosing the spring, the spring supports and the retainer between them and being conformed to the shape of that portion of the insole of a shoe which is under the heel and instep of the wearer. 115 120

3. The arch support set forth adapted to rest on the inside of a shoe and comprising a horse-hide glove leather bottom substantially conforming to the space to be covered 130

by the heel and instep of the wearer's foot, leather spring supports in the form of pads mounted on the above leather bottom approximately at the mid-width thereof and 5 forwardly of the portion of said bottom which is to support the heel; an arched crowned leaf spring, the ends of which rest upon the leather spring-supports; an arched crowned leaf spring fitted to the crown of 10 the arched leaf spring; a flexible retainer over said springs and leather spring supports, the edges of said retainer being secured by suitable means to the leather spring

supports and the bottom; and a prime sole leather top conforming in contour to the 15 glove-leather bottom; said top and bottom being secured together at the edges by suitable means.

In testimony whereof I have hereunto set my hand at Los Angeles, California, this 20 11th day of March, 1914.

ELOF ANDERSON.

In presence of—

JAMES R. TOWNSEND,
L. BELLE WEAVER.
